UNITED STATES PATENT OFFICE.

JOHN H. SMITH, OF JACKSON, MICHIGAN, ASSIGNOR TO WITHERINGTON AND COOLEY MANUFACTURING COMPANY, OF SAME PLACE.

DESIGN FOR AN AGRICULTURAL FORK.

SPECIFICATION forming part of Design No. 14,544, dated January 8, 1884.

Application filed April 13, 1883. Term of patent 14 years.

To all whom it may concern:

Be it known that I, JOHN H. SMITH, of Jackson, in the county of Jackson and State of Michigan, have invented a new and original Design for Agricultural Forks, of which the following is a specification, reference being had to the accompanying drawings, in which—

Figure 1 is a perspective view of a fork embodying said design with a portion of the handle attached. Fig. 2 is a plan view of the fork.

The design relates, principally, to agricultural forks having four tines, but can be applied to a fork of a greater number of tines, if desired.

The fork represented in the drawings is a four-tine fork.

The design has relation to what is known as the "head" of the fork, and its characteristic feature resides in the V form given to that portion of the bar of the fork between the two center tines, as indicated at *a*, with the fork-shank *b* at the angle or apex of the V, thus making a graceful and pleasing connection between the tines and the shank.

What I claim, and desire to secure by Letters Patent, is—

The design for agricultural forks, hereinbefore described, and represented in the accompanying drawings.

J. H. SMITH.
